UNITED STATES PATENT OFFICE.

FRANK J. BASSO, OF BROOKLYN, NEW YORK.

WRENCH.

1,185,465.

Specification of Letters Patent. Patented May 30, 1916.

Application filed February 15, 1916. Serial No. 78,442.

To all whom it may concern:

Be it known that I, FRANK J. BASSO, a citizen of the United States, residing at Brooklyn, in the county of Kings and State of New York, have invented certain new and useful Improvements in Wrenches; and I do hereby declare the following to be a full, clear, and exact description of the invention, such as will enable others skilled in the art 10 to which it appertains to make and use the same.

The primary object of this invention is to provide a novel type of wrench, that can be quickly adjusted to accommodate the different sizes of nuts and which is provided with a pair of auxiliary jaws, which may have sharpened edges, one of which auxiliary jaws is movable and adapted to be moved in the direction of the other auxiliary 20 jaw, during the adjustment of the main jaws of the wrench.

Another object of the invention is to so mount the auxiliary jaws that they may be relieved of considerable strain, when in operative position, and also to admit of their immediate removal when it is desired to substitute new ones.

Other objects will appear and be better understood from that embodiment of my invention of which the following is a specification, reference being had to the accompanying drawings forming a part thereof, in which:

Figure 1 is a side view of the wrench 35 showing the main jaws and the auxiliary jaws in opened position, Fig. 2 is bottom plan view of the wrench shown in Fig. 1, Fig. 3 is a side view of the wrench showing the main and auxiliary jaws in operative 40 position, Fig. 4 is a view showing the other side of the wrench shown in Fig. 3, Fig. 5 is a detail sectional view taken on the line 5—5 of Fig. 1, Fig. 6 is horizontal detail sectional view taken on the line 6—6 of Fig. 45 2, Fig. 7 is a perspective view of the connecting ends of the handle of the wrench, Fig. 8 is a detail longitudinal sectional view, taken through the shank of the stationary jaw of the wrench.

50 Referring to the drawings more in detail, the numeral 1 designates a handle, having its opposite sides provided, adjacent its inner end, with beveled faces 2, and the said inner end of the handle is bifurcated, to provide the fingers 3 and 4. Associated with the handle 1, is a stationary jaw designated

5, which is provided with an elongated shank 6, the lower free end of which is received between the fingers 3 and 4 and is provided with a transverse opening which registers 60 with similar transverse openings in the fingers 3 and 4 for the reception of a pivot pin 8. The sides of the shank 6, are provided at points below the jaw 5 with recesses, in which recesses are mounted plates 9 and 10, 65 the said plates being held within the recesses by means of fastening elements 11 which extend through the plates 9 and 10 and through the shank 6. The plates 9 and 10 have portions which project beyond the 70 inner side of the jaw and shank 5 and 6, and a plate 12 is interposed between the projected portions of the plates 9 and 10 and secured thereto in any suitable manner. The plate 9 has its upper edge terminating short 75 of the upper edge of the plate 10 and provides a seat for a jaw 13, which has a shank 13' extending throughout the length of the plate 9, and the said jaw is held in place by means of the fastening element 15 which 80 extends through the shank of the jaw 13 and through the shank 6 which carries the jaw 5. The jaw 13 is preferably provided with a cutting edge 16.

Coöperating with the stationary jaw 5 is 85 a movable jaw 18 carried by an elongated shank 17 which is slidably positioned between the extended portions of the plates 9 and 10, and has its lower end positioned between the upper end of arcuately shaped 90 links 19 and 20, and pivoted thereto by means of the pivot pin 21. The lower ends of the links 19 and 20 lie on the opposite sides of the handle 1 against the faces 2, and are secured thereto by means of a transversely extending pivot pin 22.

The shank 17 has that side adjacent the plate 9 provided with a recess 23 located at the upper end of the shank 17 and receives a flanged portion 24 which is carried by the 100 jaw 25, which jaw is arranged in alinement with the jaw 13 and preferably provided with a beveled cutting edge 26, and the said jaw 25 is adapted to be held in position by a transversely extending bolt 27 which extends 105 through the flanged portion 24 and the shank 17 and has its outer end received by a nut 28 which is adjustable against the adjacent side of the shank 17.

By virtue of mounting the jaw 25 in the 110 recess 23 and mounting the lower jaw 13 on the upper edge of the plate 9, the fastening

means 15 and 27 will be relieved from strain when the jaws 16 and 25 are moved against an article placed therebetween.

Having thus described my invention, I claim:

A wrench comprising a stationary jaw, a shank carried by the stationary jaw, a movable jaw, a shank carried by the movable jaw and extending in parallel relation 10 with the shank of the stationary jaw, a handle having one end pivoted to the shank of

the stationary jaw and arcuately shaped links pivotally connected to the shank of the movable jaw and the handle so as to effect movement of the shank of the movable 15 jaw when the handle is operated.

In testimony whereof I affix my signature in presence of two witnesses.

FRANK J. BASSO.

Witnesses:

JOHN J. HOEFLINGER,
JOE BARCE.
